(57) **CLAIM**

The ornamental design for the battery charger, as shown and described.

DESCRIPTION

The patent or application file contains a least one drawing executed in color. Copies of this patent or patent application publication with color drawing(s) will be provided by the Office upon request and payment of the necessary fee.

FIG. 1 is a perspective view of a battery charger of the present invention;

FIG. 2 is a front view of the battery charger of FIG. 1;

FIG. 3 is a rear view of the battery charger of FIG. 1;

FIG. 4 is a left side view of the battery charger of FIG. 1;

FIG. 5 is a right side view of the battery charger of FIG. 1;

FIG. 6 is a top view of the battery charger of FIG. 1; and,

FIG. 7 is a bottom view of the battery charger of FIG. 1.

The broken lines shown in the drawings illustrate portions of the battery charger that form no part of the claimed design.

1 Claim, 7 Drawing Sheets
